UNITED STATES PATENT OFFICE.

WILLIAM H. MINER, OF CHAZY, NEW YORK.

RAILWAY DRAFT-RIGGING.

1,301,961.

Specification of Letters Patent. Patented Apr. 29, 1919.

Application filed March 4, 1918. Serial No. 220,224.

To all whom it may concern:

Be it known that I, WILLIAM H. MINER, a citizen of the United States, residing at Chazy, in the county of Clinton and State 5 of New York, have invented a certain new and useful Improvement in Railway Draft-Rigging, of which the following is a full, clear, concise, and exact description, reference being had to the accompanying drawings, forming a part of this specification.

This invention relates to improvements in railway draft riggings.

As is well known, in operation of railway cars, the draft gears thereof are subject to 15 much heavier shocks in buff than they are in draft. Consequently, it is desirable that a shock absorbing mechanism of very high capacity be employed in buff and that a gear of lighter capacity be employed in draft in 20 order to facilitate starting of trains inasmuch as a gear of sufficient capacity to absorb the buffing shocks might prove too "stiff" to permit easy starting under draft.

The object of my invention is to provide 25 a friction shock absorbing mechanism for railway cars which will have the desired heavy frictional capacity in buff and the lighter spring capacity in draft for the greater portion of the draft movement combined with a short frictional capacity at the 30 end of the draft movement to absorb any excessive draft shocks.

In the drawing forming a part of this specification, Figure 1 is a longitudinal, vertical, sectional view of a portion of a railway draft rigging showing my improvements in connection therewith. Fig. 2 is a horizontal, sectional view, taken substantially on the line 2—2 of Fig. 1 and illustrating the position of the parts in normal 40 condition or under full release. Figs. 3 and 4 are transverse, vertical, sectional views, taken on the line 3—3 and 4—4, respectively of Fig. 1.

In said drawings, 10—10 denote casting 45 center or draft sills of a railway car to the inner faces of which are secured stop castings A—A. Each of the stop castings A has a rear main stop shoulder 11, a front 50 main stop shoulder 12, a front limiting stop shoulder 13 and what may be termed an auxiliary front stop shoulder 14.

The friction gear, hereinafter described, is mounted between the stop castings and 55 is operatively connected to the draw bar 15 by a yoke 16, the yoke and draw bar being

pivottally connected by a heavy bolt 17 to permit radial movements of the draw bar. Within the yoke is a front follower 18 which normally engages the set of front main stop 60 shoulders 12—12. All the parts of the gear are supported in operative position by a saddle plate 19 detachably bolted or otherwise suitably secured to the bottom flanges of the stop castings A—A. 65

The improved friction shock absorbing mechanism, as shown, includes a casting B, said casting B comprising a substantially cylindrical friction shell 20 at the front end and a rectangular spring casing 21 at the rear of the shell, said spring casing 21 being open at the sides to thereby permit the insertion laterally of twin-arranged main springs 22—22. The rear end of the casing 21 is formed with an integral wall 23 which acts as a rear follower and normally engages the set of rear main stops 11—11. Said rear wall 23 is provided with a rearwardly extending enlargement 24 which is recessed to accommodate a correspondingly shaped extension 25 on an auxiliary spring follower 26 mounted within the casing 21 and the function of which is hereinafter described. 70 75 80

Coöperable with the friction shell 20 is a series of friction shoes 27 having a wedge 28 mounted therewithin, there being anti-friction rollers 29 between the shoes and wedge. The wedge 28 is extended forwardly and engages the front follower 18, as clearly shown in Figs. 1 and 2. The 90 friction shoes 27 are extended within the friction shell 20 so as to engage a forwardly extending collar or annular flange 30 formed on a front spring follower 31 mounted within the casing 21 and against which bear the 95 forward ends of the main springs 22. Said collar 30 telescopes within the rear end of the friction shell so as to properly guide the follower 31, and in order to place the main springs 22 under an initial compression, blocks 33—33 are inserted through diametrically disposed openings in said collar 30 to thereby space the follower 31 from the inner end of the friction shell 20. Between the follower 31 and the friction shoes is 100 105

located a comparatively light spring 34 which bears at its rear end against said follower 31 and at its front end against a small follower or washer 35. A retaining bolt 36 extends from the wedge 29 to the follower 110 31 and holds all the friction elements in proper position, as will be understood.

It will be noted that the casting B, hereinbefore described, is so designed as to form a pair of laterally extended shoulders 37-37 at the front end of the casing 21 and said shoulders 37-37 are normally spaced a short distance from the auxiliary front shoulders 14 for the purpose hereinafter described, said space in actual practice being made approximately one-half inch.

10 The operation is as follows: Upon inward or buffing movement of the draw bar, the casting B will be held stationary against the rear stop shoulders 11 and inward movement of the front follower 18 will cause the 15 friction elements to act throughout the entire inward stroke, the main springs 22 of the gear being in action during this entire movement. In this manner, the maximum capacity of the friction mechanism is obtained so as to take care of the heavy buffing 20 shocks. In draft, forward movement of the draw bar and yoke will force the rear spring follower 26 forwardly until the rear portion of the yoke engages the rearward extension 25 24 of the casting B. During this portion of the movement, which in actual service will approximate two inches, the casting B will remain stationary due to the fact that the friction between the friction shoes and the 30 shell 20 will be sufficiently greater than the capacity of the springs 22 to permit the compression of the latter without moving the casting B. After the springs 22 have been compressed sufficiently for the rear end of 35 the yoke 16 to engage the rear portion of the casting B, it is evident that the latter will then be forced forwardly during the last half inch or so of the draft movement and until the shoulders 37-37 come into 40 engagement with the auxiliary front stops

14. During this last half inch movement, it is evident that friction will be generated, thus augmenting the shock absorbing capacity during the last or ultimate portion of the draft movement. In this manner, I obtain 45 an easy spring action under draft for the greater portion of the draft movement and at the same time provide sufficient additional frictional capacity to absorb any excessive draft shocks. 50

Although I have herein shown and described what I now consider the preferred manner of carrying out the invention, the same is merely illustrative and I contemplate all changes and modifications that come with 55 in the scope of the claim appended hereto.

I claim:

In a railway draft rigging, the combination with draft sills, of stop castings secured to the inner faces thereof, each of said castings having a rear main stop, a front main stop and an auxiliary front stop, a friction shell having shoulders at its rear end normally engaging said rear main stops and provided also with shoulders near its front end normally spaced a predetermined distance from said auxiliary front stops, friction elements coöperable with said friction shell, a follower interposed between said elements and the front main stops, spring 60 means within said shell coacting with said friction elements, a draw bar, yoke-acting means, and a rear spring follower movable relatively to the friction shell for a limited 65 distance under draft. 70

In witness that I claim the foregoing I have hereunto subscribed my name this 18th day of Feb., 1918. 75

WILLIAM H. MINER.
